STRINGED MUSICAL INSTRUMENT

Elbern H. Alkire, Easton, Pa.

Application April 18, 1949, Serial No. 2,098

Term of patent 14 years

(Cl. D56—1)

To all whom it may concern:

Be it known that I, Elbern H. Alkire, a citizen of the United States residing at Easton, in the county of Northampton and State of Pennsylvania have invented a new, original, and ornamental Design for Stringed Musical Instruments, of which the following is a specification, reference being had to the accompanying drawing, forming part thereof.

Fig. 1 is a top plan view of a stringed musical instrument, showing my new design;

Fig. 2 is a perspective view thereof; and

Fig. 3 is a side elevational view thereof.

The back of the instrument is conventional.

I claim:

The ornamental design for a stringed musical instrument, as shown and described.

ELBERN H. ALKIRE.
